US00D862412S

(12) **United States Design Patent** (10) **Patent No.:** **US D862,412 S**
(45) **Date of Patent:** **** Oct. 8, 2019**

(54) **HEADPHONE**

(71) Applicant: **Harman International Industries, Incorporated**, Northridge, CA (US)

(72) Inventor: **Jinwon Yook**, Shenzhen (CN)

(73) Assignee: **Harman International Industries, Incorporated**, Northridge, CA (US)

(**) Term: **15 Years**

(21) Appl. No.: **29/627,685**

(22) Filed: **Nov. 29, 2017**

(51) LOC (12) Cl. **14-01**

(52) U.S. Cl.

USPC **D14/205**; D14/223

(58) **Field of Classification Search**

USPC D14/223, 205; 181/129, 130, 135;

(57) **CLAIM**

The ornamental design for a headphone, as shown and described.

DESCRIPTION

FIG. 1 is a perspective view of a headphone showing the new design;

FIG. 2 is a front elevational view thereof;

FIG. 3 is a rear elevational view thereof;

FIG. 4 is a side elevational view of one side thereof;

FIG. 5 is a side elevational view of the opposite side thereof;

FIG. 6 is a top plan view thereof;

FIG. 7 is a bottom plan view thereof;

FIG. 8 is a perspective view of an opposite-handed embodiment of the headphone of FIG. 1;

FIG. 9 is a front elevational view thereof;

FIG. 10 is a rear elevational view thereof;

FIG. 11 is a side elevational view of one side thereof;

FIG. 12 is a side elevational view of the opposite side thereof;

FIG. 13 is a top plan view thereof; and,

FIG. 14 is a bottom plan view thereof.

The broken lines immediately adjacent the shaded areas represent the bounds of the claimed design, while all other broken lines are directed to environment and are for illustrative purposes only; the broken lines form no part of the claimed design.

1 Claim, 14 Drawing Sheets
